UNITED STATES PATENT OFFICE

ALEXIS NAERT, OF DETROIT, MICHIGAN

STOCK-FEEDING COLLET

Application filed December 17, 1928. Serial No. 326,580.

My invention relates to a new and useful improvement in a stock feeding collet adapted for use particularly for feeding stock to screw machines.

5 It is an object of the present invention to provide a collet which will effectively grip the stock when feeding it into the machine and release when moving to a rearward position for engaging the stock at another point.

10 It is another object of the present invention to provide a stock feeding collet of this class which will be simple in structure, economical of manufacture, and highly efficient and durable in use.

15 Another object of the invention is the provision of a stock feeding collet having a minimum number of parts and one which is easily and quickly assembled.

Other objects will appear hereinafter.

20 The invention consists in the combination and arrangement of parts hereinafter described and claimed.

The invention will be best understood from a reference to the accompanying drawings 25 which form a part of this specification, and in which,

Fig. 1 is a side elevational view of the invention.

Fig. 2 is a longitudinal, vertical sectional view of the invention.

Fig. 3 is a sectional view taken on line 3—3 of Fig. 2.

The invention is illustrated in the drawing as attached to a tube 7 which is commonly found on screw machines and utilized for assisting in feeding the stock into the machine.

The invention comprises a cylindrical portion 8 having the reduced threaded portion 9 which is threaded into the tube 7 and through 40 which extends the bore 10 which is enlarged at 11 to provide a sleeve 12 which is threaded at one end. This sleeve is provided with a plurality of axially directed slits so that dirt and other foreign material may not accumulate in the sleeve 12. Positioned in the

sleeve 12 is a coil spring 14 adapted to embrace the work piece or stock 21 which is to be fed in the work machine. Engaging against one end of the spring 14 and loosely positioned in the sleeve 12, is a collar 17 having its end face 18 tapered and adapted to engage the tapered ends of the semi-cylindrical gripping members 15 and 16 which are also loosely positioned in the sleeve 12. These gripping members when engaging each other at their edges, form a cylinder of less diameter than the inside diameter of the sleeve 12. Threaded into the open end of the sleeve 12 is a plug 19 having its inner face tapered as at 20 for engaging the tapered ends of the gripping members 15 and 16.

In use, when the parts are assembled as shown in Fig. 2 and the stock 21 projected therethrough, the engagement of the inclined faces 20 and 18 with the tapered ends of the gripping members 15 and 16 will force them inwardly so as to securely clamp the stock 21. The spring 14, through the pressure on the collar 17 serves to retain these members normally in clamping position and when the plug 19 is threaded inwardly sufficiently to adjust the tension of the spring 14 to the desired stock, the gripping members 15 and 16 will grip the stock sufficiently to feed it into the machine and at the same time permit the withdrawal rearwardly on the stock of the feeding mechanism for obtaining another grip on the stock.

With a stock feeding mechanism as now used, particularly where a spring gripping member is provided by slitting, much delay is encountered because of fracture in the gripping mechanism. With a stock feeding mechanism of this class, a durable structure is provided which will successfully perform its function under normal conditions without repair or adjustment. By threading the plug 19 inwardly or outwardly, the tension of the spring 14 may be regulated so that the

2
degree of clamping of the gripping members 15 and 16 may be determined.

While I have illustrated and described the preferred form of my invention, I do not wish to limit myself to the precise details of structure shown but desire to avail myself of such variations and modifications as come within the scope of the appended claims.

Having thus described my invention what I claim as new and desire to secure by Letters Patent is:

1. A stock feeding mechanism of the class described, comprising: a sleeve bearing member; a coil spring loosely positioned in said sleeve; a collar axially slid able in said sleeve and engaging at one face one end of said spring, the opposite face of said collar being inclined inwardly toward its center; a pair of semi-cylindrical gripping members loosely positioned in said sleeve and having tapered ends and each engaging at one end on its periphery the inclined face of said collar; and means insertable in said sleeve for engaging the peripheries of the opposite ends of said gripping members.

2. A stock feeding mechanism of the class described, comprising: a sleeve bearing member; a coil spring loosely positioned in said sleeve; a collar axially slid able in said sleeve and engaging at one face one end of said spring, the opposite face of said collar being inclined inwardly toward its center; a pair of semi-cylindrical gripping members loosely positioned in said sleeve and having tapered ends and each engaging at one end on its periphery the inclined face of said collar; and means insertable into said sleeve having an inner face inclined inwardly toward its center for engaging the peripheries of the opposite ends of said gripping members.

3. A stock feeding mechanism of the class described, comprising: a sleeve bearing member; a spring positioned in said sleeve; a collar axially slid able in said sleeve and engaging at one face one end of said spring, the opposite face of said collar being inclined inwardly toward its center; a pair of gripping members loosely positioned in said sleeve and having tapered ends and engaging on its periphery at one end the inclined face of said collar; a plug threaded into said sleeve having its inner face inclined inwardly toward the center and engageable with the peripheries of the ends of said gripping members.

4. A stock feeding mechanism of the class described, comprising: a cylindrical member having a bore formed therein, said bore being enlarged to provide a sleeve; a coil spring loosely positioned in said sleeve; an angular member loosely positioned in said sleeve and engaging at one face one end of said spring, the opposite face being inclined inwardly toward its center; a pair of semi-cylindrical gripping members having tapered ends and inserted in said sleeve and engaging at one

of their ends on the peripheries of said inclined face; and a plug threaded into the open end of said sleeve and having its inner face inclined inwardly toward its center and engageable with the peripheries of the opposite ends of said gripping members for cooperating with said collar for forcing said gripping members radially inwardly toward each other into clamping relation with a work-piece projected therethrough.

In testimony whereof I have signed the foregoing specification.
